Primary Examiner — Sandra L Morris(74) *Attorney, Agent, or Firm* — Kelly G. Swartz;
 Widerman Malek, PL(57) **CLAIM**

The ornamental design for a spool shaped lidded container, as shown and described.

DESCRIPTION

FIG. 1 is a perspective view of a spool shaped lidded container according to the present invention.

FIG. 2 is a front elevation view of the spool shaped lidded container of FIG. 1.

FIG. 3 is a rear elevation view of the spool shaped lidded container of FIG. 1.

FIG. 4 is a first side elevation view of the spool shaped lidded container of FIG. 1.

FIG. 5 is a second side elevation view of the spool shaped lidded container of FIG. 1.

FIG. 6 is a top plan view of the spool shaped lidded container of FIG. 1.

FIG. 7 is a bottom plan view of the spool shaped lidded container of FIG. 1; and,

FIG. 8 is a perspective view of the spool shaped lidded container of FIG. 1 with a lid removed.

The broken lines shown in the drawings illustrate features of the spool shaped lidded container that form no part of the claimed design.
